(57) **CLAIM**

The ornamental design for a penis extension with harness, as shown and described.

DESCRIPTION

FIG. 1 is a front elevational view of a penis extension with harness showing my new design, with the rear elevational view being a mirror image thereof;

FIG. 2 is a right side elevational view thereof, with the left side elevational view being a mirror image thereof;

FIG. 3 is a top plan view thereof;

FIG. 4 is a bottom plan view thereof; and,

FIG. 5 is perspective view thereof.
